Application filed February 15, 1897. Serial No. 623,574. Term of patent 14 years.

To all whom it may concern:

Be it known that I, JOHN C. MILLER, of Waterbury, in the county of New Haven and State of Connecticut, have invented a new Design for a Bicycle-Lamp Body; and I do hereby declare the following, when taken in connection with the accompanying drawings and the letters of reference marked thereon, to be a full, clear, and exact description of the same, and which said drawings constitute part of this specification, and represent, in—

Figure 1, a rear perspective view of a bicycle-lamp body containing my design; Fig. 2, a view thereof in side elevation.

My invention relates to a design for a bicycle-lamp body; and it consists in the configuration hereinafter described, and shown in the accompanying illustration.

My newly-designed lamp-body comprises a main or body portion A, rectangular in general form, but having its four corners A' set inward and concaved. From the top of the said body portion rises a cylindrical collar B, having beads b b and a row of perforations b'. From the bottom of the said body portion depends a neck C, having a row of perforations c and terminating in an outwardly-flaring flange c'. A large flaring lens-holding collar D extends forward from the front of the body portion A, than which it is larger in diameter. 25 The rear face of the body portion is provided with a large circular cap E, approximately corresponding to it in diameter and having a centrally-arranged boss E', surrounded by a raised ring E², having a circular series of perforations E³ formed in it. 30

I claim—

The design for a bicycle-lamp body, as herein shown and described.

In testimony whereof I have signed this 40 specification in the presence of two subscribing witnesses.
